CLAIM

The ornamental design for a nightlight, as shown and described.

DESCRIPTION

FIG. 1 is a perspective view of a first embodiment of a nightlight;

FIG. 2 is a front view of the nightlight of FIG. 1;

FIG. 3 is a rear view of the nightlight of FIG. 1;

FIG. 4 is a right side view of the nightlight of FIG. 1;

FIG. 5 is a left side view of the nightlight of FIG. 1;

FIG. 6 is a top plan view of the nightlight of FIG. 1;

FIG. 7 is a bottom plan view of the nightlight of FIG. 1;

FIG. 8 is a perspective view of a second embodiment of a nightlight;

FIG. 9 is a front view of the nightlight of FIG. 8;

FIG. 10 is a rear view of the nightlight of FIG. 8;

FIG. 11 is a right side view of the nightlight of FIG. 8;

FIG. 12 is a left side view of the nightlight of FIG. 8;

FIG. 13 is a top plan view of the nightlight of FIG. 8; and,

FIG. 14 is a bottom plan view of the nightlight of FIG. 8.

The broken lines immediately adjacent to the shaded areas depict the bounds of the claimed design, while all other broken lines are directed to environment.

1 Claim, 12 Drawing Sheets
